US0D1076057S

(12) **United States Design Patent** (10) **Patent No.:** **US D1,076,057 S**
(45) **Date of Patent:** **** May 20, 2025**

(54) **PORTABLE ULTRASONIC NEBULIZER**

(71) Applicant: **Feellife Health INC.**, Guangdong (CN)

(72) Inventors: **Jian Hua**, Guangdong (CN); **Linsi Lan**, Guangdong (CN)

(73) Assignee: **Feellife Health INC.**, Shenzhen (CN)

(**) Term: **15 Years**

(21) Appl. No.: **29/921,576**

(22) Filed: **Dec. 18, 2023**

(30) **Foreign Application Priority Data**

Nov. 30, 2023 (CN) 202330786551.5

(57) **CLAIM**

The ornamental design for a portable ultrasonic nebulizer, as shown and described.

DESCRIPTION

FIG. 1 is a top, front, left-side perspective view of a portable ultrasonic nebulizer showing our new design;

FIG. 2 is a bottom, rear, right-side perspective view thereof;

FIG. 3 is a top, front, right-side perspective view thereof;

FIG. 4 is a front elevational view thereof;

FIG. 5 is a rear elevational view thereof;

FIG. 6 is a left-side elevational view thereof;

FIG. 7 is a right-side elevational view thereof;

FIG. 8 is a top plan view thereof; and,

FIG. 9 is a bottom plan view thereof.

The broken lines shown in the drawings depict portions of the portable ultrasonic nebulizer that form no part of the claimed design.

1 Claim, 9 Drawing Sheets
